UNITED STATES PATENT OFFICE

EDWARD CHARLES FREDERICK OAKLEY, OF NORBURY, ENGLAND

NONRETURN VALVE

Application filed February 25, 1931, Serial No. 518,160, and in Great Britain February 28, 1930.

This invention relates to non-return valves and in particular to valves for use in connection with petrol pumps although they may be used for various other purposes, and it has for its object a construction which will prevent any dirt or foreign matter which may be suspended in or be carried by the liquid, from settling in close proximity to or between the valve and its seating, thereby preventing the proper closing of the valve.

To attain this end the valve is formed so that the fluid passing therethrough rotates said valve, and when pumping has ceased, the continued rotation of the valve sets up a centrifugal action of the fluid thereby throwing any foreign matter that may be contained in said fluid away from the valve seat, said foreign matter falling into an annular chamber provided below the valve and its seating.

In the accompanying drawings which illustrate this invention:

Figure 1 is a sectional elevation of one embodiment of the invention;

Figure 2 is a plan thereof;

Figure 3 is an underneath plan thereof;

Figure 4 is a similar view to Figure 1, of part of a valve, illustrating a modification;

Figure 5 is a sectional elevation of a further embodiment of the invention;

Figure 6 is an underneath plan thereof;

Figure 7 is a plan view of the valve removed from the valve casing;

Figure 8 is a sectional view of the valve seating removed from the casing, and

Figure 9 is a plan thereof.

In the embodiment illustrated in Figures 1 to 3 the valve casing is formed in two parts 1 and 2 and the seating 3 for the main valve 4 is arranged at the top of an upwardly extending tubular part 5 provided on the part 1, the diameter of the part 5 being such that when the part 2 is attached thereto, an annular chamber 6 is formed around the extension

5. The valve 4 is provided on its periphery with a plurality of angularly disposed vanes 7 or other means for enabling the fluid passing through said valve to set up a rotative action of said valve. The valve seating 3 may be of the usual mushroom type as shown in Figure 1, or as shown in Figure 4, it may be formed V-shaped or with an equivalent sharp edge and the underside of the valve plate 26 may be formed flat as shown at 8 in Figure 4 so as to provide a minimum of contact surface between the fixed and moving parts of the valve. The valve 4 is furnished on its underside with a centrally arranged stem 9 adapted to slide vertically and rotate in a sleeve 10, 50 concentrically supported by webs 11 in the part 1 of the casing. The stem 9 is bored to receive the stem 12 of a second valve 13 adapted to seat on a collar 14 secured in the part 1 of the casing. The valve 13 is so arranged 55 or formed that the fluid may leak past same slowly for the purpose hereafter referred to.

The upper part 2 of the valve casing is provided with a perforated part, bridge or stop 15 with which a projection 16 on the top of the valve 4 is adapted to contact so as to prevent the upper face of said valve 4 seating against the upper face of the valve casing, thereby retarding or preventing the 60 passage of the fluid.

The possible lift of the main valve 4 is arranged to be greater than the lift of the valve 13 so that the latter valve will close 65 before the main valve.

According to a modification the valve and 70 its seating may be formed substantially as shown in Figure 4, that is, the valve seating may have a V-shaped or equivalent sharp edge adapted to coact with a flat surface on the valve.

According to a further embodiment of the 75 invention illustrated in Figures 5 to 9, the valve seating 3a is provided on a part 17 formed separately from and having a sliding fit within the casing 18, which is fur- 80 85 90

nished with an annular knife edge 19 adapted to bear against the upper face 20 of the part 17, which forms the bottom of the annular chamber 6a, to make a fluid tight joint 5 between the two parts, or if desired, the annular knife edge may be formed on the part 17 adapted to coact with a shoulder on the part 18. The part 17 is maintained in position by means of the nut 21, the inner top 10 surface 22 of which also forms a seating for the valve 13a secured to the lower end of the stem 12a.

The main valve 4a is in this construction provided with but four vanes 7a and its maximum elevation is limited by a split ring 23, placed in a groove 24 formed at the lower end of the stem 9a, the lower part of the sleeve 10a concentrically supported by webs 11a being recessed as shown so as to provide 20 a shoulder 25 for the ring to bear against.

The part 26a of the main valve 4a adapted to coact with the valve seating 3a may be formed in one with said valve, but said coacting part is preferably formed separately therefrom in the form of a hard steel washer and soldered or otherwise secured thereto and ground.

In operation, the fluid being delivered, first lifts the lower or second valve and then the 30 main valve which immediately commences to rotate, but immediately pumping ceases the second valve drops onto its seat and prevents the immediate fall of the fluid in the pipe and also by reason of the slight cushioning effect prevents the main valve falling too rapidly on its seat so as to enable the rotative movement of said valve to throw out any foreign matter that might otherwise come between the valve face and its seating. 35 The leakage of fluid past the second valve provides the necessary suction on the underside of the main valve so as to permit the pressure of the fluid above said main valve to press same on its seating.

45 What I claim is:

1. A non-return valve for controlling the flow of fluids, comprising in combination a casing, a valve seating therein, a valve coacting with said seating, a plurality of angularly disposed vanes on the periphery of the head of said valve, a part screwed into the lower end of the casing below the first named valve seating, a seating formed on the inner surface of said part, a light flat 50 plate valve coacting with said seating, the two valves being so arranged that the light plate valve closes first and permits the fluid to leak slowly past, thereby for a short period maintaining fluid pressure below the 55 first named valve for preventing the too rapid closure thereof.

2. A non-return valve for controlling the flow of fluids, comprising in combination a casing formed in two parts, a tubular part 60 provided on one of said parts arranged to ex-

tend into the other of said parts and to form an annular chamber around said extension, a valve seating formed on said tubular part, a sleeve supported within said tubular part, a valve coacting with said valve seating, a stem on said valve sliding in said sleeve, angularly disposed vanes on the periphery of the head of said valve, a collar screwed into the lower part of said casing below the bottom of the stem on the valve and a light flat 70 plate valve coacting with said seating.

3. A non-return valve for controlling the flow of fluids, comprising in combination an outer casing, an inner part having a sliding fit within said outer casing, means comprising a nut for maintaining said inner part in position, a valve seating formed at the top of said inner part, a sleeve supported in said part, a valve arranged above and coacting with said valve seating, a depending stem on said valve sliding in said sleeve, angularly disposed vanes on the periphery of the head of said valve, a valve seating formed on the nut for maintaining the said inner part in position, and a light flat plate valve coacting with said seating.

4. A non-return valve for controlling the flow of fluids, comprising in combination an outer casing, an inner part having a sliding fit within said outer casing, means for making a fluid tight joint between said parts and means comprising a nut for maintaining said inner part in position, a valve seating formed with a sharp edge at the top of said inner part, a concentrically disposed sleeve supported in said part, a flat faced valve coacting with said valve seating, a stem on said valve sliding in the concentrically disposed sleeve, a plurality of angularly disposed vanes on the periphery of the head of said valve, and means for limiting the lift of said valve, a second valve seating located below the bottom of the stem on the flat faced valve formed on the nut for maintaining the said inner part in position, a 95 plate valve coacting with said seating and a stem on said plate valve arranged to slide in the stem of the first named valve.

5. A non-return valve for controlling the flow of fluids, comprising in combination an outer casing, an inner part having a sliding fit within said outer casing, means comprising an annular knife edge on the interior of the casing adapted to coact with the upper face of the inner part for making a fluid tight joint between said parts and means comprising a nut for maintaining said inner part in position, a tubular extension provided on the top of said inner part, a valve seating formed with a sharp edge at the top of said extension, a concentrically disposed sleeve supported in said inner part, a flat faced valve coacting with said valve seating, a plurality of angularly disposed vanes on the periphery of the head of said valve, a stem on said 100 105 110 115 120 125 130

valve sliding in the concentrically disposed sleeve, means comprising a split ring seated in a groove in said stem for limiting the lift of the valve, a second valve seating located 5 below the bottom of the stem on the flat faced valve formed on the nut for maintaining the said inner part in position, a plate valve coacting with said seating and a stem on said plate valve arranged to slide in the 10 stem of the first named valve.
